FIG. 6.

FIG. 7.

FIG. 8.

FIG. 1 is a perspective view of a lighting fixture illustrating my new design;

FIG. 2 is a front elevational view thereof;

FIG. 3 is a top plan view thereof;

FIG. 4 is a side elevational view thereof;

FIG. 5 is a bottom plan view thereof;

FIG. 6 is a front elevational view of a second embodiment of my design;

FIG. 7 is a front elevational view of a third embodiment of my design; and

FIG. 8 is a front elevational view of a fourth embodiment of my design.

The cross hatching of the refractor in FIGS. 7 and 8 indicates conventional faceting and is partially shown for convenience of illustration, it being understood that the faceting is uniformly continuous over the area indicated.

I claim:

The ornamental design for a lighting fixture, as shown and described.
